William M. MacKenzie
Inventor

By his Attorney *MacKenzie*

UNITED STATES PATENT OFFICE.

WILLIAM M. MACKENZIE, OF YONKERS, NEW YORK.

TENNIS NET.

Application filed July 24, 1922. Serial No. 576,976.

To all whom it may concern:

Be it known that I, WILLIAM M. MACKENZIE, a citizen of the United States, residing in Yonkers, county of Westchester, 5 State of New York, have invented a certain new and useful Improvement in Tennis Nets, of which the following is a specification.

The present invention relates to an improved construction for finishing tennis nets, whereby greater security is obtained together with a greatly improved appearance and increased durability.

The machines used for manufacturing tennis netting are all adapted to the production of a diamond or rhomboidal mesh. Square meshes are used in the accepted forms of tennis nets, that is to say, meshes in which the cords run vertically and horizontally 20 when the net is in position. This is obviously necessary to permit of properly stretching the net without distortion. Consequently the netting must be severed on the bias in cutting out each individual net. This gives 25 a square mesh, but at the same time leaves severed cord ends which ravel and produce an unsightly fringe along the lower edge of the net.

Hitherto it has been customary to bind the 30 lower edge to a longitudinal tension rope by means of a "simming" or "seaming" cord, in finishing a tennis net; but the frayed or ravelled ends of cord become loose, and give an unsightly appearance. Moreover, if the simming cord becomes accidentally severed at 35 one point it is liable to become progressively loosened along its length, thereby freeing the net from the lower tension rope.

My invention overcomes these objections 40 and does away with the tension rope, producing a finish which is more sightly and durable besides being less subject to shrinkage in case of being wetted.

The invention is illustrated in a preferred 45 form in the accompanying drawings wherein Figure 1 is an elevation of a stretched tennis net constructed in the manner common hitherto, Figure 2 is an enlarged view in elevation of a part of the lower edge of 50 the old form of net showing the common mode of attachment to the lower tension rope, Figure 3 is a similar view showing my improved binding partly broken away, Figure 4 is a sectional view on the line 4-4 of 55 Figure 3, and Figure 5 is a front view on a smaller scale of the bottom of my improved

net showing the extension of the binding for purposes of attachment.

In Figure 1 is shown a specimen of the old form of net 10, attached to posts 11, 12 (or 60 equivalent supports) by extensions of the upper tension rope 13 and lower tension rope 14.

A portion of the lower edge of the old form of net is shown in Figure 2. The vertical sides of the meshes are shown at 15, joined by knots 16 in a well known manner to the horizontal sides 17.

Owing to the necessary cutting of the netting (as made by machinery) on the bias, 70 to produce the square meshes shown, the cut ends of the vertical cords are left free, and very soon ravel out as shown at 18.

To secure the lower edge of the net and to provide means for stretching and attaching the net at the bottom, it has been customary to supply a rope 14, to which the lowermost meshes of the cut net are secured by a "simming" cord 19 which extends parallel and in contact with the rope 14. This 80 cord is given two half hitches around the lowermost horizontal cords 17 at each point of junction with a vertical cord 15. This is clearly shown in Figure 2. Of course, if the simming cord 19 should become accidentally 85 severed, it would become loose at one knot after the other, thus partly releasing the net from the rope 14. This effect would be accelerated by the shaking and the blows constantly received by the net in the course of 90 play.

In my improved binding, the rope 14 is dispensed with, and a firm canvass (or similar cloth) tape is doubled lengthwise and applied to the lower edge of the net, as 95 shown in Figures 3 and 4 at 20.

In Figure 3, a portion of the tape is broken away to show the exposed and unbound condition of the net. On the right hand side of Figure 3 the dotted lines show 100 how the lowermost horizontal mesh cord 17 lies at the bottom of a long pocket or channel formed by the middle bend in the tape 20, the sides of which are brought together and united throughout the entire length of 105 stitching 21. The ravelled ends 18 are snugly bound against the cord 17, being entirely concealed by the tape 20. These features are also brought out in Figure 4, which is a sectional view on the line 4-4 in Figure 3. 110

As shown in Figure 5, the ends of the doubled tape 20, beyond the ends of the net

are extended, as at 22 and 23 to form means for fastening the net to side posts in any desired manner. This tape 20 is made of closely woven and slightly absorbent material, and its tendency to shrink when wetted is much less than that of the rope 14 commonly used.

What I claim is—

In a tennis net, a tape longitudinally folded along and over the lowermost mesh cords

of the net and extended sufficiently to provide fastening means for the lower part of the net, said tape having its two sides brought together and stitched near their edges, so as to conceal the mesh cords, their knots, and the ravelled ends of the severed cords.

In testimony whereof I have hereto set my hand on this 21st day of July, 1922.

W. M. MACKENZIE.
